UNITED STATES PATENT OFFICE.

ISAAC MAMAUX, OF PITTSBURG, PENNSYLVANIA, ASSIGNOR OF TWO-THIRDS
TO JOHN C. WOODS, OF SAME PLACE, AND JOHN T. KELLY, OF ALLEGHENY, PENNSYLVANIA.

DESIGN FOR A BOTTLE.

SPECIFICATION forming part of Design No. 24,957, dated December 10, 1895.

Application filed November 12, 1895. Serial No. 568,745. Term of patent 14 years.

To all whom it may concern:

Be it known that I, ISAAC MAMAUX, of Pittsburgh, in the county of Allegheny and State of Pennsylvania, have invented a new and original Design for Bottles, of which the following is a full, clear, and exact description, reference being had to the accompanying drawings, forming part of this specification, in which—

The design consists in a bottle having a surface pattern substantially as shown in the accompanying drawings and as herein described.

As shown in the drawings, the bottle 2 has a scroll 3 extending across the bottle, having at the ends representations of horns 4, above which are crosses 5 6.

2c

I claim—

The design for a bottle substantially as herein shown and described.

In testimony whereof I have hereunto set my hand.

ISAAC MAMAUX.
